Primary Examiner — Paula Allen Greene*(74) Attorney, Agent, or Firm* — Alonzo & Associates;
Arlyn Alonzo(57) **CLAIM**

The ornamental design for a headphone headset, as shown and described.

DESCRIPTION

FIG. 1 is a perspective view of a headphone headset showing my new design, the opposite front face of the interior headphone headset ear cup is a mirror image.

FIG. 2 is a front view thereof.

FIG. 3 is a back view thereof.

FIG. 4 is a left side view thereof.

FIG. 5 is a right side view thereof.

FIG. 6 is a top view thereof; and

FIG. 7 is a bottom view thereof; and,

FIG. 8 is a perspective view of a second embodiment of a headphone headset, wherein the front view, back view, left side view, right side view, top view and bottom view thereof are the same as represented in FIGS. 2, 3, 4, 5, 6 and 7, respectively, the opposite front face of the interior headphone headset ear cup is a mirror image.

The design is a headphone headset.

The headphone headset may be used for listening to music and/or audio signals from a transmitting device.
